UNITED STATES PATENT OFFICE

LUDWIG DILLINGER, OF FAIRVIEW, NEW JERSEY

DESIGN FOR A DOLL KITCHEN

Application filed May 21, 1929. Serial No. 31,321. Term of patent 3½ years.

To all whom it may concern:

Be it known that I, LUDWIG DILLINGER, a citizen of the United States, residing at Fairview, in the county of Bergen and State of New Jersey, have invented a new, original, and ornamental Design for Doll Kitchen, of which the following is a specification, reference being had to the accompanying drawing, forming part thereof.

The figure is a perspective view of a doll kitchen showing my new design.

I claim:

The ornamental design for a doll kitchen, as shown.

LUDWIG DILLINGER.
